UNITED STATES PATENT OFFICE.

JOHN C. ENGLISH, OF CAMDEN, NEW JERSEY, ASSIGNOR TO VICTOR TALKING MACHINE COMPANY, A CORPORATION OF NEW JERSEY.

DESIGN FOR A CABINET FOR TALKING-MACHINES.

41,776.

Specification for Design.

Patented Sept. 12, 1911.

Application filed August 27, 1910. Serial No. 579,353. Term of patent 14 years.

To all whom it may concern:

Be it known that I, JOHN C. ENGLISH, a citizen of the United States, and a resident of the city of Camden, State of New Jersey, have invented a certain new, original, and ornamental Design for a Cabinet for Talking Machines, of which the following is a specification, reference being had to the accompanying drawing, forming a part thereof.

The figure is a perspective elevational view of a cabinet for a talking machine showing my new design.

What I claim is:

The ornamental design for a cabinet for talking machines as shown.

JOHN C. ENGLISH.
